ABSORBENT SEALING CAP

Joaquin Montané Martí and Agustín Fitó Piñol,
Buenos Aires, ArgentinaApplication March 29, 1941, Serial No. 385,932
In Argentina December 18, 1940

2 Claims. (Cl. 15—133)

This invention relates to a novel and improved type of absorbent sealing cap, to be applied to bottles and similar containers and substantially has for its object a novel type of such device provided on its outer surface with means adapted to absorb the fluid material contained in the container and be kept in a suitable condition of impregnation or imbibition, so as to allow of said absorbent and impregnated means to be used by rubbing against or on any desired surface, for the treatment of the same with said fluid material.

Owing to its convenient features of construction and arrangement, the improved type of sealing cap which forms the object of this invention, may conveniently be used for cleaning clothes and the like, although it may as well be used for treating other surfaces for any desired purposes.

The invention also views other objects which will appear and be understood from the following description of the device.

In order that the invention may be readily understood and carried into practice without difficulty, a preferred embodiment of the same has been shown by way of example in the accompanying illustrative drawing which shows a partial longitudinal section of a container for fluid material, provided with the novel type of sealing cap in accordance with this invention.

In the form of construction shown, the reference number 1 indicates a bottle or similar container for fluids, of the usual type, the neck 2 of which is formed on its outer surface with screw threads 3, for screwing thereon a corresponding screw cap. The lower part of the neck is formed with a plain section 4 which provides a seat for a washer 5 of cork or other suitable material, for securing a tight closure of said cap.

According to this invention, the sealing cap substantially consists of a nozzle member 6, provided on its inner surface with screw threads 7, adapted to engage with the threaded part 3 of the neck 2, the outer surface of the cover being slightly tapering or conical in shape and ending at its base part, of largest diameter with a peripheral flange or shoulder 9, adapted to bear with its lower edge on the aforementioned washer 5, thus forming a perfectly tight closure.

By reference to the drawing it will also be seen that in the upper surface of said nozzle member 6, a recess 10 of suitable depth is formed, adapted to house a disc 11, of felt or other suitable absorbent material, of which the outer surface 12, slightly spherical in shape, is covered by

an applicator fabric in the form of a changeable piece of cloth or similar material 13, held in position by a suitable ring or hoop 14 which may be applied with an adjustable degree of pressure around the external surface 8 of said cover 6.

To the lower end of the nozzle member 6, a thin disc 15 is applied, so as to act as a packing between the base of said nozzle member and the rim of the neck 2, thereby forming a tight seal between both parts.

If necessary, an annular groove 16 and a central recess 17 may be formed on the upper and lower faces, respectively, of the nozzle member 6, the former of the same being filled with the same material which forms the disc 11.

It will further be seen, by referring to the drawing, that at the central part of the end wall of the nozzle member 6, another small recess 18 is formed, directed toward the lower end of the same and extending in a downward direction so as to form a small frangible appendix or extension 19, partially provided with a narrow longitudinal duct 20 and formed on its outer surface with a peripheral groove 21 which serves as a seat for the rim of a narrow opening formed at the centre of the disc 15. Within the recess 18, a small spherical valve 22 is housed, adapted to obturate the outlet of the duct 20.

The whole device, as above described, is covered at its upper end with a second cover 23, screwed onto the screw threads 24 provided on the outer surface of the peripheric rim 9, while its lower edge is adapted to tightly bear on the washer 5, mentioned before.

The extension 19 which obturates the outlet of the duct 20 has for its object to prevent any leakage of the fluid contained in the container 1, owing to evaporation or to any other cause, while serving at the same time to warrant the purchaser as to the genuineness of said contents, since said extension only is to be detached when initiating the use of the same, for which purpose it will be sufficient to disengage the nozzle member 6 and cover 23 and then break or tear said extension along the groove 21, after which the parts 6 and 23 may be replaced in position.

For using the device above described, the outer cover 23 is removed, the position of the container 1 is reversed, so as to cause the valve 23 to open under the action of its own weight, thereby allowing of the discharge of a suitable amount of the fluid contained in the container by the duct 20, until the pad of felt or the like, formed by the disc 11 and the outer lining 12 has become sufficiently impregnated or imbibed; after this,

the said pad may be rubbed against the cloth or other surface to be treated for cleaning the same or for other purposes. After this, the container is reverted to its normal position, whereby the seal of the valve 22 will close and the outer cover or cap 23 is finally replaced in position.

When the device is being used as a means for cleaning stains, it will be necessary to replace from time to time the cover or lining 13, for which purpose the hoop or ring 14 is removed and after a fresh lining having been placed in position, the hoop 14 is again forced home, against the conical surface 8.

From the foregoing description, the invention will have clearly been understood and no further explanation will be required by those skilled in the art.

Having now particularly described and ascertained the nature of our said invention and in what manner the same is to be performed, we declare that what we claim and desire to secure by Letters Patent is:

1. An applicator container device wherein the container is provided with an externally threaded neck, said device including an internal- 25

ly threaded nozzle member for engaging the threaded neck of the container and having an end wall at the bottom of a recess formed in its outer end, said wall being provided on its outer face with a cavity providing a ball seat and also provided on its inner face with a frangible tubular extension whose bore communicates at one end with said ball seat and which bore is otherwise closed until the extension is fractured, a sealing disc at the inner side of said end wall and having a central opening whose edge portion engages said extension to hold the same therewith, a porous disc fitted in said recess and enclosing a ball located in said ball seat, an applicator fabric releasably fitted to the nozzle over said disc, and a cover detachably connected to said nozzle member.

2. An applicator container device according to claim 1 wherein the outer surface of the frangible tubular extension is provided with an external groove, and the edge portion of the central opening is interlocked with said groove.

JOAQUIN MONTANÉ MARTÍ.
